APPARATUS FOR TREATING GASES

Ernst Sander, Dessau, Germany

Application October 18, 1934, Serial No. 748,972
In Germany May 31, 1933

4 Claims. (Cl. 62—119)

The invention relates to an apparatus for treatment of gases or vapors which behave like gases or mixtures thereof, hereinafter designated gas for simplicity. The apparatus involves the absorption of the gas by circulating liquid in contact with a diaphragm through which the gas passes, and boiling out the absorbed gas in a space, and delivery of the gas into another space. The apparatus is particularly useful for refrigeration systems.

According to my invention gas is continuously passed from one space through a diaphragm into a liquid in another space. The last said space consists of two parts. A hydrostatic pressure is maintained in the part in contact with the diaphragm, that is the gas absorbing part, by boiling the degassed liquid from the other part, that is, from the boiling part, over a dividing partition into the absorbing part. The two parts of the liquid space are connected so that the two said parts are under equal gas pressure. As a result of the hydrostatic pressure head a circulation of liquid takes place so that cool liquid flows to and along the diaphragm while warm liquid flows away from the diaphragm.

The diaphragm through which the gas passes into contact with the absorption liquid is specially constructed in view of the particular gas to be used and consists of material which would absorb the gas rather than permit it to pass through it, but which gives up the gas to the liquid having a stronger tendency to absorb it.

The diaphragm can be a porous mass, for example, burnt clay, artificial stone, or like products of organic or inorganic material. It can be a single or multiple layered body and, if desired, may have separated layers. It can be covered with layers of adsorption material which absorb gas more weakly than the liquid, for instance, turf dust. As such adsorption material, turf dust, inorganic materials, mixtures of organic and inorganic substances, or layers of such materials, which possess gas absorbing qualities are useful. The diaphragm itself may also consist of such adsorption substances in compressed condition, whereby the gas absorption takes place very effectively and rapidly.

The diaphragm can be provided with good heat conductors. These can also surround the diaphragm or be placed within or outside the diaphragm. In this way, a uniform distribution of absorption heat, or good heat dissipation is attained, and at the same time a good resistance against stress caused by pressure difference and the like is attained.

The diaphragm can have the form of a closed hollow body into which the gas inlet pipe enters, or the form of a one or more separated, layered head walls between a liquid chamber and a gas chamber. The diaphragm can also be part of a wall having gas channels, or may comprise filling material in a space which lies between the liquid and gas spaces.

For aiding the diffusion a constant current can be passed to the diaphragm.

In order to absorb the gas, it may be conducted along one or more absorption walls continually in contact with unsaturated absorption liquid. For this purpose, several semipermeable walls can be used each of which is in combination with a different circulation of absorption liquid.

By this means gas can be brought from lower to higher pressure. Furthermore, reduced pressure can be produced in this way.

Preferably, this apparatus is applied for the treatment or absorption of methylamine, which is of importance as a cold producer for refrigeration.

The treatment of gas and its absorption according to the invention is particularly useful for absorption type refrigerators.

In the drawings several embodiments of the new apparatus are illustrated.

Figs. 1 and 2 diagrammatically illustrate two embodiments of absorption-boiler plants;

Fig. 3 diagrammatically illustrates an entire plant of an absorption refrigerator;

Figs. 4 and 5 show embodiments of walls of the absorption chamber;

Figs. 6-8 illustrate expansion chambers for the evaporation of liquid gases;

Fig. 9 shows a special type of absorption substance between the gas and liquid spaces; and

Figs. 10 and 11 show special plants for the circulation of the absorption liquid according to the device shown in Fig. 9.

It will be seen from Figs. 1 and 2 that in the boiling out process, the exchange of heat and the absorption of the gas may take place in one vessel.

Numeral 1 designates a metallic vessel, 4 the boiler with the heating tube 2, 3 a heating element, 5 a tubular body, consisting, if desired, of metal, which can be suitably enlarged at the lower end in the form of an inverted funnel. 50 Numeral 6 is the diaphragm allowing gas to pass through, but impervious to liquid, by means of which the gas is brought into contact with the absorption liquid. Numeral 7 is the gas chamber communicating with an evaporator, not shown, 55

through the medium of the piping 8. Numeral 9 is a filter intended for trapping the water which has been carried along, while 10 represents a pipe connection leading to a condenser, not shown.

This arrangement is intended for being heated electrically. The vessel 1 is charged with the absorption liquid to such an extent, that a part of the tube 5 projects from the liquid. If the electric heating element 3 is operated, the liquid, contained within the heating space or chamber 4, will be strongly heated. The gas will be boiled out and the degasified liquid will flow over the tube 5. The level of the liquid will tend to be equalized automatically, in consequence of which the degasified liquid drops outside of the heating space or chamber 4. Owing to the contact with the gas passing through wall 6 in the absorption space or zone, it will be again charged with gas and passes through the tubular body 5 to the chamber 4 again where it is heated.

The ribs 11 serve for the purpose of dissipating the surplus heat.

In accordance with Fig. 2 the heating tube 2 is positioned at the side of the tube 5 and provided with a lateral aperture corresponding with a similar aperture in the wall of the vessel 1.

This arrangement is intended for being heated by means of a flame or through the medium of hot gases. The process of boiling, the exchange of heat, the cycle of the liquid, and of absorption is similar to that of the device according to Fig. 1.

The funnel-shaped portion of tube 5 should cover at least part of the absorption chamber or space.

In Fig. 3 the boiler is indicated by 12. Numeral 13 indicates a liquid extraction vessel, 15 the liquifier, 16 the expansion nozzle, 17 the evaporator, 18 the re-cooler, and 19 the absorber. In 40 the boiler 12 gas, which may be methylamine, is driven out of the absorption liquid, which may be water, by boiling with the aid of the heater 2, whereby the degasified liquid flows into the vessel 13 via the overflow 22. This causes the liquid 45 to pass into the absorber 19 through the pipe 20 and further, through pipe 21 into the boiler 12. The boiled out gas escapes from the precipitating vessel 13 via a filter type liquid extractor 14 into the liquifier 15, where, owing to the elimination 50 of heat, the gas is rendered liquid. Flowing through the nozzle 16 into the evaporator 17, the gas will evaporate owing to the drop in pressure. Subsequently the gas is made to pass into the re-cooler 18, in connection with which the liquified 55 gas is sub-cooled, finally being taken up by the solvent within the porous cylinder in the absorber.

In Figs. 4 and 5 a porous body or diaphragm 23 is surrounded by adsorption substance 24 which absorbs the gas rather than permits the gas to pass through it, such as peat dust (Torfmull), silica-gel or the like. A metal plate 25 having openings or formed of metal bands holds such gas absorption substance in place. 65 A metallic framework 26 may be provided for strengthening the structure and for dissipation of heat. Numeral 8 is the connection pipe from the evaporator, 27 the connection pipe from the boiler and 28 the connection pipe to the boiler.

70 In Fig. 6 the evaporator chamber 29 is provided with good heat conductors 30, which may form

a framework. As shown in Figs. 7 and 8, the good heat conductors may surround the chamber as metallic plate 31 which may have openings formed therein or may consist of metallic bands. The conductors may also be formed as a cellular system as at 32, in Fig. 7. Also a packing of metallic chips or the like may be arranged surrounding the chamber, as in Fig. 8. The mentioned arrangements may also be used in combination.

Further, the evaporator chamber may have the heat conductors distributed in the body walls.

The chamber walls may be of organic substance as peat dust (Torfmull) or organic artificial substances as porous or microporous hard or soft 15 rubber or metal sponge.

The liquified gas may enter into the chamber as liquid or in sprayed state.

The thickness and size and direction of the porosity or the degree of the mechanical condensation of the evaporator chamber can be modified in consequence of different mechanical stresses. For carrying these mechanical stresses a framework may be provided.

In Figs. 9 to 11 the vessel 39, extending between 25 vessel 1 and the vessel 40, is filled with absorption material and has openings in the walls contacted by the liquid in the vessel 1, and also in the walls contacted by the gas in the vessel 40, flowing from the evaporator. Vessel 40 is a 30 buffer space, which may be provided. The tube 5 conducts the liquid from below to the absorber and around it. The boiler 4 is preferably of small cross section.

It is advantageous that the absorption refrigerator and the cooling space be so built that the boiler with all heat supplying parts be placed outside the heat insulation, and preferably in an air channel of sheet metal, and the evaporator inside the heat insulation, while the conduction 40 of the liquified gas to the evaporator and the conduction of expanded gas from the evaporator can be through heat insulation.

An absorption refrigerator, especially of small dimensions, according to the invention is cheap 45 and works without any danger.

I claim:

1. A diaphragm for use in absorption refrigeration comprising a semi-permeable wall which is impermeable to absorption liquid but permeable 50 to refrigerant gas, said wall having good heat conductors comprising metal bands which envelop said wall so that a good distribution of the absorption heat and a good heat dissipation takes place and the mechanical stress produced by 55 pressure difference and the like effects are borne securely by the diaphragm.

2. A diaphragm as claimed in claim 1, the semi-permeable wall of which consists of material 60 which absorbs the gas rather than permitting the gas to pass through it.

3. A diaphragm as claimed in claim 1, in which the wall is a closed hollow body and consists of a plurality of layers, one of which is a material 65 which absorbs the gas rather than permitting the gas to pass through it.

4. A diaphragm as claimed in claim 1, and a metallic framework within the semi-permeable wall.

70 ERNST SANDER.
